US0D1002843S

(12) **United States Design Patent** (10) **Patent No.:** **US D1,002,843 S**
Wang et al. (45) **Date of Patent:** **** Oct. 24, 2023**

(54) **NECK BRACE**

(71) Applicants: **Jiang Wang**, Jiangsu (CN); **Jiangsu Alphay Medical Devices Co., Ltd.**, Jiangsu (CN)

(72) Inventors: **Jiang Wang**, Jiangsu (CN); **Guifeng Yang**, Jiangsu (CN)

(73) Assignees: **Jiang Wang**, Jiangsu (CN); **Jiangsu Alphay Medical Devices Co., Ltd.**, Jiangsu (CN)

(**) Term: **15 Years**

(21) Appl. No.: **29/747,692**

(22) Filed: **Aug. 25, 2020**

(51) **LOC (14) Cl.** **24-02**

(52) **U.S. Cl.**

USPC **D24/191**

(58) **Field of Classification Search**

(57) **CLAIM**

The ornamental design for a neck brace, as shown and described.

DESCRIPTION

FIG. 1 is a front perspective view of the neck brace showing our new design.

FIG. 2 is a rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the drawings illustrate portions of the neck brace and form no part of the claimed design.

1 Claim, 8 Drawing Sheets
